ATTORNEYS

UNITED STATES PATENT OFFICE.

PHILIP H. UNSINGER, OF GENEVA, NEW YORK, ASSIGNOR TO GENEVA CUTLERY CORPORATION, OF GENEVA, NEW YORK, A CORPORATION OF NEW YORK.

SAFETY-RAZOR.

1,323,730.

Specification of Letters Patent.

Patented Dec. 2, 1919.

Application filed May 14, 1919. Serial No. 297,044.

To all whom it may concern:

Be it known that I, PHILIP H. UNSINGER, of Geneva, N. Y., in the county of Ontario, in the State of New York, have invented 5 new and useful Improvements in Safety-Razors, of which the following, taken in connection with the accompanying drawings, is a full, clear, and exact description.

This invention relates to improvements in 10 mounts for razor blades and what are commonly called safety razors.

The object of this invention is to produce a mount which will hold, in operative position, the ordinary commercial blade used in 15 safety razors, cheap and durable in construction and of great utility.

The invention relates more particularly to the detailed construction and operation thereof, the advantages of which will more 20 fully appear from the following description taken in connection with the drawings in which—

Figure 1 is a perspective view of the safety razor mount looking at it from the 25 rear, in closed position holding the blade.

Fig. 2 is a section on line *a—a*, Fig. 1.

Fig. 3 is a section on line *b—b*, Fig. 2.

The razor mount comprises a base plate 30 —1— preferably formed of sheet metal, having its front portion bent downwardly, as shown at 2, from the body of the plate and preferably lying at an obtuse angle to the body of the plate to constitute, when formed as hereinafter described, a guard 35 bar —3— and a series of upwardly extending guard teeth —4—.

For this purpose the plate —1— has a portion cut away to form an elongated opening —5— bordered by relatively narrow 40 side walls —6— which together with the bar —3— from which the teeth —4— extend, constitute the guard bar for the razor. The series of guard teeth —4— project into the opening —5— when the front portion 45 of the plate —1— is bent downwardly about an axis extending through the intermediate portion of the side walls —6—, these teeth extending preferably forwardly toward a blade —8— when properly seated within 50 the mount. The opening —5— extends some distance to the rear of the front edge of the blade —8—, and, as the teeth —4— terminate beneath the blade, there is left a free passage between the blade for lather, 55 etc., the front edge of the blade at the side

portions being supported by the side walls —6— which in turn are provided with stops —9— to properly limit and hold the blade —8— in position. These stops —9— may be formed in any suitable manner, as by 60 punching up parts of the plate —1—, or in any other suitable manner. The blade —8— is held in place upon the base —1— by a holding and clamping member —10— connected to the rear of the base for pivotal or rocking movement to permit the separation of the parts to an extent, thereby allowing removal of the blade and to permit the easy cleaning of the structure. For 65 this purpose the clamping plate is formed 70 with the substantially flat body portion —11— and one edge thereof bent substantially U-shape, as shown in Fig. 2, and having its rear edge portions formed with any suitable number of eyes —12— adapted to 75 engage and register laterally with eyes —13— upon the rear edge of the plate —1— so as to form a pivot in connection with the rod —14—. While I have shown a number 80 of these eyes, I preferably use a lesser number for the reason that it is much easier to keep the mount clean by using a lesser number.

The plate —1— upon its rear face is provided with a boss —15— and it and the 85 plate are preferably interiorly threaded, as shown, to receive the handle —16— which is provided with a shoulder —17— and a threaded portion —18—, terminating in the end —19— which is reduced in size and 90 which has upon one face a recess —20— for the purpose which will be presently explained. 21— is a spring rod shown best in Fig. 3 mounted at each end in the flanges —22— of the plate —11— so that when the 95 clamping member, holding the razor blade, is forced downwardly, this rod —21— will engage or snap into the recess —20— and hold the clamping member, which in turn carries the blade in a locked position. 100

To remove the blade, it is only necessary to exert pressure on the rear edge of the clamping member which will disengage the rod —21— from the recess —20— and allow it to rock sufficiently to remove the blade. 105

It will be readily seen that, instead of passing the end of the handle through the base and providing a boss upon its lateral face, the inner face of the base may be provided with a recessed boss or lug with which 110

the spring may engage for the purpose of holding the clamping member in locked engagement with the base.

What I claim is:—

- 5 1. A mount for a razor blade, comprising a base, one edge of which terminates in a guard, a clamping member hinged to said base and adapted to hold a blade therein, a handle adapted to be inserted through said base, its end having a recess upon its lateral face and a spring engaging said recess to retain the clamping member in operable position.
- 10 2. In a safety razor a base, a clamping member pivotally secured to the base, a handle member connected to the base, one of said members having means disposed between the clamping member and the base, for removably engaging the other member.
- 15 3. A mount for a razor blade, comprising a base having a boss upon its outer face, one edge of which base terminates in a guard, a clamping member hinged to said base adapted to retain a blade therein, a handle having a portion extending through said boss and base the end of said handle having means upon its lateral face for engaging a spring, and a spring mounted within the clamping member for the purposes set forth.
- 20 4. In a safety razor, a base member and 30 a handle member secured thereto, one of said members having a part projecting from the base on the side of the base opposite the body of the handle and formed with a recess, a clamping member mounted on 35 the base and having a spring rod movable into said recess for removably securing the parts in position to confine a razor blade.
- 25 5. In a safety razor a base, a clamping member, a handle secured to the base and 40 means carried by the clamping member in advance of its said pivot for removably engaging the said handle to secure the parts in proper position to confine a razor blade.
- 30 6. In a safety razor a base, a casing-like 45 clamping member pivotally mounted on the base, a handle secured to the base and a spring rod mounted in the clamping member and removably engaging the said handle to secure the parts in proper position to 50 confine a razor blade.

In witness whereof I have hereunto set my hand this 3rd day of May 1919.

PHILIP H. UNSINGER.
